UNITED STATES PATENT OFFICE.

REINHARDT DAAE, OF PITTSBURGH, PENNSYLVANIA.

GRATE FOR GAS PRODUCERS.

Application filed December 7, 1920. Serial No. 428,851.

To all whom it may concern:

Be it known that I, REINHARDT DAAE, a citizen of the United States, residing at Pittsburgh, Allegheny County, Pennsylvania, have invented a new and useful Improvement in Grates for Gas Producers, of which the following is a full, clear, and exact description.

The present invention relates broadly to 10 gas producers, and more particularly to rotary grates for use with such producers.

An important object of the present invention is to provide a rotary grate having means for water cooling the same to increase 15 the life thereof.

Another object of the present invention is to provide a rotary grate having a series of openings so located that air may be blown therethrough in a direction opposite to the 20 direction of rotation of the grate.

Still another object of the invention is to provide mechanical devices for preventing the clogging of such openings by ashes.

An additional object of the invention is 25 to so position the air openings that the tendency thereof to become clogged is reduced to a minimum, and an effective distribution of air throughout the body of the fuel within the producer is obtained.

30 A further object of the invention is to provide a rotary grate of such contour and configuration that clinker formations are destroyed and the accumulation of ashes above the grate is prevented.

35 A still further object of the invention is to construct a grate of the character described in sections, in such a manner that parts thereof may be removed and renewed as found necessary.

40 The foregoing and other objects, together with their attendant advantages will be apparent as the invention becomes better understood from the accompanying specification and drawings forming a part thereof, 45 it being premised that various changes may be made in the details of construction without departing from the spirit of the invention as defined in the claims.

In the drawings,—

50 Figure 1 is a vertical section through the lower portion of a gas producer constructed in accordance with the present invention, the section being on line I—I of Figure 2.

55 Figure 2 is a transverse sectional view on line II—II of Figure 1.

Figure 3 is a plan view, on an enlarged scale and partly broken away, illustrating a portion of the rotary grate.

Figure 4 is a sectional view of the grate as 60 illustrated in Figure 1, on an enlarged scale.

With rotary grates as heretofore constructed for use in gas producers, there has been an irregular upper surface presented to the fuel body within the producer, of such shape that ashes have not moved freely 65 thereover to discharging position. Also, the air openings in the grates have been located in such manner that the same tend to become clogged during operation of the 70 grate and thereby destroy their usefulness. The present invention aims to overcome these objections and to provide a sectional rotary grate construction having greater length of life than constructions heretofore utilized.

75 Referring more particularly to the drawings, there is illustrated a producer body 2 of any desired construction carried by supports 3 on a base 4. The base is provided with the usual pit 4^a and passageway 4^b, 80 permitting the repair of the producer when shut down, as is customary in constructions of this nature.

85 Mounted on the base 4 is a race-way 5 carrying antifriction devices 6 for supporting a rotatable bottom plate 7. This bottom plate may have secured thereto in any desired manner, a ring worm gear 8 adapted to mesh with a worm 9 on a transversely extending shaft 10 suitably journaled on 90 the base 4. The shaft 10 may have secured thereto a ratchet wheel 11 adapted to be rotated by a pawl 12 pivotally secured to a lever 13 which is oscillated by a pitman 14 controlled by an eccentric or other form 95 of drive 15. The pitman 14 may be adjustably connected to the lever 13, whereby the amplitude of oscillation of the lever may be varied as desired to change the rate of rotation of the bottom plate 7.

100 The bottom plate also carries an angularly projecting flange 16 which, with the downwardly projecting flange 17 formed on the producer body, provides a water seal 18 for the lower end of the producer.

105 The rotary grate proper comprises a main bottom portion 19, generally conical in shape, and preferably constructed of two halves 20 and 21 which may be joined along the section line I—I of Figure 2, in any de-

sired manner. This bottom portion may be formed as a casting to provide a series of hollow chambers 22 extending radially from the center of rotation C of the grate. These 5 chambers each have curved upper surfaces 23 extending from the back to the front thereof, and are so shaped as to provide substantially vertical, radially extending faces 24 between adjacent chambers. The height 10 of the faces preferably gradually decreases from the center of the grate outwardly, as is clearly shown in Figure 2. This construction provides a smooth surface along which the ashes may gradually and uniformly 15 move to discharging position. The bottom portion 19 is mounted on a carrier 25 which is generally elliptical in horizontal cross section, to conform to the base of the bottom portion 19 of the grate, which is similarly 20 shaped. This shape is very desirable, as during the operation of the grate the distance between the periphery thereof and a fixed point of the body of the producer 25 gradually changes by increasing or decreasing, to effect a breaking up of clinker formations which tend to lodge at the bottom of the fuel bed.

Secured to the top of the bottom sections 20 and 21 of the grate is a substantially 30 conical shaped top section 26. This section 26 is preferably hollow to provide a water chamber 27, and is truncated to provide a flat top 28, the entire area of the top being eccentric and lying entirely on one side of 35 the center of rotation C of the main body of the grate. This location of the flat portion 28 is desirable, as during rotation of the grate the body of ashes above the same is constantly shifted whereby a pillar of accumulated ashes on the flat top portion of 40 the grate is prevented. The top section 26 is also preferably provided with curved faces 29 and intermediate vertical faces 30 joining alternate corresponding faces 24 of 45 the bottom portion of the grate. It will be apparent that the entire construction is such that discharge of ashes into the water seal 18 is facilitated. From this point they 50 may be removed, as is customary in the art, by a suitable plow or scraper 31.

For water cooling both the top and bottom portions of the grate, there may be provided a water inlet pipe 32 having a portion thereof coinciding with the center 55 of rotation C of the grate and projecting into the water chamber 27 in the top portion thereof. From this chamber the water may overflow through pipes 33 into the lower part of the bottom portion 19 of the grate to fill the hollow chambers 22 therein. These chambers are in turn provided with an outlet pipe 34 discharging into a pocket 35 in the base 4 and forming, with the flange 36, a supplemental water 60 seal 37 for the bottom plate 7. In this man-

ner, the grate may be continuously supplied with a cooling medium which will result in increased life for the grate.

Discharging into the interior of the hollow portion of the grate, is an air supply 70 pipe 38 for maintaining at all times a predetermined air pressure within the grate body. This air is permitted to escape into the fuel within the producer through a series of arcuate openings 39 formed in 75 the vertical faces 24 and 30, respectively, of the grate portions, and preferably located at substantially the base of each of the faces. In practice, power is applied to the shaft 10 in such manner that the grate 80 will be rotated in the direction of the arrow A, Figure 2, whereby the air is discharged through the openings 39 in a direction opposite to the direction of rotation of the grate. Due to the location of 85 the openings, and the direction in which the air is projected therethrough, the openings have a tendency to remain free from ashes and other foreign matter tending to clog the same. In order to insure this condition, 90 however, there is provided a mechanically operable agitating or cleaning device, 95 cooperating with each of the openings. As illustrated in the drawings, this device may comprise a series of radially extending rods 100 40 pivotally connected to the lower ends of a series of vertically extending levers 41, each having a pivotal mounting 42 carried by the bottom of the chambers 22. The upper end of each of the levers 41 is bent to project rearwardly, opposite to the direction of rotation of the grate, to form 105 cleaning fingers 43 extending into the arcuate openings 39. For oscillating the cleaning fingers 43 in the openings 39 during rotation of the grate, the ends of the rods 40 are connected by links 44 to bell crank levers 45 having pivotal mountings 46 carried by the bottom plate 7. Each of the bell crank levers 45 carries on its lower 110 end a roller 47 adapted to be held in contact with a cam 48 by a spring 49. The cam 48 is provided with any desired number of projections 50 adapted to engage the rollers 47 and move the same outwardly 115 against the action of the springs 49 to reciprocate the rods 40 and oscillate the levers 41. It will be apparent that in this manner a periodical mechanical cleaning of each 120 of the openings is insured.

The advantages of the present invention arise from the provision of a rotary grate so constructed that the same may be continuously supplied with a cooling medium.

Further advantages arise from the shape of the grate permitting the gradual movement of the ashes thereover and preventing the accumulation of pillars of ashes above the same.

Still further advantages of the inven-

tion arise from the provision of air openings for projecting air into the fuel body in a direction opposite to the direction of rotation of the grate, and having mechanical means for preventing the same from clogging.

I claim:

1. As a new article of manufacture, a rotary grate for gas producers having a plurality of separable sections, said sections having closed chambers, and means for delivering cooling fluid to the chambers of said sections, substantially as described.
2. As a new article of manufacture, a rotary grate for gas producers having closed fluid chambers, there being openings through the grate between the fluid chambers, and means for circulating fluid through the chambers, substantially as described.
3. As a new article of manufacture, a rotary grate for gas producers having closed fluid chambers, extending in a general radial direction, there being air openings through the grate between the fluid chambers, and means for circulating the fluid through the fluid chambers, substantially as described.
4. As a new article of manufacture, a rotary grate for gas producers having closed fluid chambers, extending in a general radial direction, there being recesses between adjacent chambers, there being air openings through the grate between said chambers opening into the recesses, and means for circulating fluid through the chambers, substantially as described.
5. As a new article of manufacture, a rotary grate for gas producers having closed fluid chambers extending in a general radial direction, having sloping tops and substantially vertical sides, there being recesses between the chambers by the tops and sides, there being openings through the grate opening into the recesses, means for rotating the grate in a direction to cause the ashes to ride upwardly over the inclined tops and thereby prevent clogging the recesses between the chambers with ashes, and means for circulating the fluid through the chambers, substantially as described.
6. As a new article of manufacture, a rotary grate for gas producers having a plurality of closed fluid chambers extending in a general radial direction and overlapping each other in planes extending through the axis of the grate and of general cutter tooth formation having rounded tops and side faces exposed to the ashes, in substantially radial planes, means for rotating the grate to cause the ashes to fall from the tops of the chambers over the sides, there being air openings between the chambers to cause air to flow through the grate in a reverse direction to the movement of the grate, and means for circulating fluid through the chambers, substantially as described.
7. As a new article of manufacture, a rotary grate having a frusto conically shaped bottom portion having a chamber closed to the atmosphere, and a conically shaped top portion detachably secured thereto, and having a chamber closed to the atmosphere, both of said portions having air openings therein and having means for the circulation of fluid through both chambers around said air openings, substantially as described.
8. As a new article of manufacture, a grate adapted to be rotated having a frusto conically shaped fluid cooled bottom portion with a chamber closed to the atmosphere, and a conically shaped fluid cooled top portion secured thereto and having a chamber closed to the atmosphere, both of said portions having means for the circulation of cooling fluid through both chambers, said top portion having a flat top located entirely on one side of the center of rotation of the grate, substantially as described.
9. A grate for gas producers, comprising a rotatable body portion, means for rotating said body portion, said body portion having a series of openings formed therein, and mechanical means operative during the rotation of said portion for cleaning said openings, substantially as described.
10. As a new article of manufacture, a rotary grate having a frusto conically shaped bottom portion with a chamber closed to the atmosphere, a conically shaped top portion removably secured thereto having a chamber closed to the atmosphere, and means for circulating fluid through both chambers, substantially as described.
11. As a new article of manufacture, a rotary grate having a bottom portion with a chamber closed to the atmosphere, a top portion secured thereto and independently removable therefrom, there being a chamber in the bottom portion closed to the atmosphere, and means for circulating fluid through both chambers, substantially as described.
12. As a new article of manufacture, a rotary grate having a frusto conically shaped bottom portion formed of two sections removably secured to each other, there being a chamber closed to the atmosphere in each section, a conically shaped top portion removably secured to the bottom portion, there being a chamber closed to the atmosphere in the top portion, and fluid circulating connections for first delivering cooling fluid to the chamber in the top portion and from said chamber to the chambers in the sections of the bottom portions, substantially as described.
13. A grate for gas producers comprising a rotatable body portion having a series of openings therein, a cleaning finger cooperating with each of said openings, and means for moving said fingers from one side of

the opening toward the other side thereof, substantially as described.

14. A grate for gas producers comprising a rotatable body portion having a series of 5 openings therein, means for supplying air to said openings, means for rotating said body, a cleaning finger cooperating with each of said openings, and means for operating said fingers from one side to the other 10 of said openings, substantially as described.

15. A grate for gas producers comprising a rotatable body portion having a series of elongated openings therein, means for supplying air to said openings, means for 15 rotating said body, a cleaning finger cooperating with each of said openings, and means for operating said fingers to cause them to move across the length of the openings during the rotation of body portion, substantially 20 as described.

16. As a new article of manufacture, a rotary grate of ellipsoidal form for a gas producer, having a plurality of substantially radially disposed ribs with sloping 25 upper faces and substantially vertical side faces, said ribs having chambers therein, means for circulating fluid through said chambers, and means for directing air across the sloping faces of the ribs in a general 30 tangential direction relative to the producer, substantially as described.

17. As a new article of manufacture, a rotary grate of ellipsoidal form having substantially radial ribs, each of said ribs having 35 vertically disposed faces, and sloping faces extending from the top of the vertically disposed faces downwardly toward the adjacent rib, there being air openings between the ribs for directing air across the sloping 40 surfaces in a tangential direction, said ribs having chambers therein, and means for circulating cooling fluid through said chambers, substantially as described.

18. As a new article of manufacture, a 45 rotary grate of ellipsoidal form having substantially radial ribs overlapping each other, each of said ribs having vertically disposed faces and sloping faces extending from the top of the vertically disposed faces downwardly 50 toward the adjacent rib, there being air openings between the ribs for directing air across the sloping surfaces in a tangential direction, said ribs having chambers therein, and means for circulating cooling fluid 55 through said chambers, substantially as described.

19. As a new article of manufacture, a rotary grate having a frusto conically shaped bottom portion provided with radially disposed ribs, said ribs having vertically disposed rear faces when considered with relation to the direction of rotation of the grate and sloping upper faces, said faces sloping upwardly and rearwardly toward the tops 60 of the rear faces, there being chambers in

said ribs, a chambered conical top portion removably mounted on the bottom portion and means for circulating fluid through said chambers, substantially as described.

20. As a new article of manufacture, a 70 rotary grate having a frusto conically shaped bottom portion provided with radially disposed ribs, said ribs having vertically disposed rear faces when considered with relation to the direction of rotation of the grate 75 and sloping upper faces, said faces sloping upwardly and rearwardly towards the tops of the rear faces, there being chambers in said ribs, a chambered conical top portion removably mounted on the bottom portion 80 and means for circulating fluid through said chambers, there being air openings extending through the rear faces of the ribs, substantially as described.

21. As a new article of manufacture, a 85 rotary grate of elliptical form having a frusto conically shaped bottom portion provided with radially disposed ribs, said ribs having vertically disposed rear faces when 90 considered with relation to the direction of rotation of the grate and sloping upper faces, said faces sloping upwardly and rearwardly toward the tops of the rear faces, there being chambers in said ribs, a chambered frusto conical top portion removably mounted on the bottom portion, the flat top of the top 95 portion being at one side of the axis of rotation of the grate, and means for circulating fluid through said chambers, substantially as described.

22. As a new article of manufacture, a hollow water cooled grate for gas producers having air distributing openings, means for circulating water through the interior of 100 said grate, and means cooperating with said 105 openings for preventing clogging thereof, substantially as described.

23. As a new article of manufacture, a hollow rotary water cooled grate for gas producers having a series of air openings extending through said grate, said openings being directed in a direction opposite that in which the grate is intended to rotate, means for supplying water to the interior of said 110 grate, means for rotating said grate, and means effective upon rotation of said 115 grate for preventing clogging of said air openings, substantially as described.

24. As a new article of manufacture, a 120 grate having a conically shaped bottom portion, a conically shaped top portion secured thereto, both of said portions having air openings therein, and means cooperating with said air openings for preventing clogging 125 thereof, substantially as described.

25. A rotary grate for gas producers having air openings therethrough, rockable means in each opening for cleaning ashes therefrom, and means for rocking said rockable means, substantially as described.

26. A rotatable grate for gas producers having air openings therethrough, an ash removing finger extending into each opening, and means for rocking said fingers from side to side of said openings, substantially as described.
27. A rotatable grate for gas producers having air openings therethrough, means to rotate said grate, an ash removing finger extending into each opening, and means actuated by the rotation of the grate for rocking said fingers from side to side of said openings, substantially as described.
28. A rotatable grate for gas producers having openings therethrough, and an ash removing finger in each opening connected to operating mechanism carried by the grate, substantially as described.
29. A gas producer having a grate, and means for producing relative rotation between the body of the producer and said grate, said grate having a series of radially extending ribs of general saw tooth form in cross section, said ribs having long sloping front faces and substantially vertical short rear faces, the curved faces at the outer ends of the ribs cooperating with the producer shell to crush clinkers and permit the passage of ashes into the ash pan, there being air openings through the rear faces, substantially as described.
30. A gas producer having a grate, and means for producing relative rotation between the body of the producer and said grate, said grate having a series of radially extending ribs of general saw tooth form in cross section having front and rear faces, said ribs at their outer ends cooperating with the producer shell to crush clinkers and permit the passage of ashes into the ash pan, the rear faces having openings formed therein for the passage of air, substantially as described.
31. A gas producer having a grate, and means for producing relative rotation be-
- tween the body of the producer and said grate, said grate having a series of radially extending ribs of general saw tooth form in cross section having front and rear faces, said ribs at their outer ends cooperating with the producer shell to crush clinkers and permit the passage of ashes into the ash pan, the rear faces having openings formed therein for the passage of air, and means for rock- 50
- ing said fingers from side to side of said openings, substantially as described.
32. As a new article of manufacture, a rotary grate for gas producers having a plurality of closed chambers extending in a general radial direction and of general cutter tooth formation, means for rotating said grate, said chambers having upper surfaces inclined upwardly and rearwardly with respect to the direction of rotation and having rear faces extending abruptly downwardly whereby the rotation of the grate causes the ashes to fall from the tops of the chambers over the rear faces, there being air openings between the chambers to 60
- direct air through the grate in a direction opposite to the rotation thereof, and means for circulating air through said openings, substantially as described.
